JIG

James A. Montgomery, Birmingham, Ala., assignor of one-half to Howard Moss, Birmingham, Ala.

Application April 24, 1936, Serial No. 76,130

4 Claims. (Cl. 209—457)

This invention relates to coal washing machines, or jigs, particularly to those known to the trade as "Montgomery Jigs", examples of which are described and claimed in Patents Numbers 998,373 and 1,949,174, issued to James A. Montgomery. Coal washing machines of this general type embody a hutch over which is located a perforated screen and a plunger reciprocable beneath the screen. The plunger is provided with valve controlled openings through which water is admitted above the plunger on its down stroke, to be forced upwardly through the screen on the up stroke. Beneath the plunger, across the lower part of the hutch, is an inclined partition wall defining a chamber beneath the plunger. The inclined wall is provided with valve controlled openings which admit water to the chamber on the upstroke of the plunger and close on the down stroke. A water supply chamber communicates with the hutch beneath the partition wall.

The action of washers of this type is consequently that of an ordinary pump. On the up stroke of the plunger, water is forced upwardly through the screen to stratify the coal thereon, while on the down stroke, water is admitted above the plunger, and there is a settling of the heavier particles of rock and slate on the screen. Washers of this type have proved to be highly efficient in the separation of slate from coal, and large numbers have been in commercial use for many years.

I have observed, however, in the operation of jigs of this type, as heretofore constructed, that when the plunger is changing its direction of movement, there is a marked strain upon the mechanism. Very heavy shafts and bearings have heretofore been necessary to withstand this strain. Even with hutch walls of heavy construction, they will be seen to move inwardly and outwardly as the plunger moves up and down. This movement finally leads to leaking and the necessity of repairs. Also, at the change of motion of the plunger, there has heretofore been a marked pounding of the valves in the plunger and the partition walls which involved undue wear and necessitated their frequent renewal.

Accordingly, the objects of my present invention are to provide a means for overcoming the beforementioned difficulties; to reduce the power required for the operation of jigs of the type designated; to provide for the design of a jig of this type with lighter, less expensive parts, and thus reduce the cost thereof; and also to provide

a jig having a longer operating life with less necessity for repair and replacement of parts.

I have found that a great amount of power has heretofore been dissipated in the operation of these jigs due principally to three factors, which are (1) the speed at which the jigs must operate for satisfactory capacity, which is about 50 strokes per minute; (2) overcoming, at each end of the plunger stroke, the inertia of the moving stream of water generated by the plunger; and (3) the necessary limitations to the ratio of the area of opening of the valves in the plunger and partition wall to the total area of the plunger, which is about 1 to 8.

I have discovered that by the provision of a simple cushioning means, the foregoing difficulties may be obviated and a smoother, more economical operation obtained. Briefly, my invention consists in the provision of a chamber adjacent the hutch, which is closed at the top to permit the compression of air therein, and open at the bottom to communicate with the water chamber between the plunger and the partition wall. With this cushioning chamber, as the plunger changes its direction of movement, the inertia of the moving stream of water is utilized to compress air in the upper part of the chamber, without shock to the mechanism, and the compressive force of the air in turn aids in accomplishing the return stroke of the plunger.

Apparatus embodying features of my invention is illustrated in the accompanying drawing, forming a part of this application, in which—

Fig. 1 is a sectional plan view of my improved jig taken along the line I—I of Fig. 2; and

Fig. 2 is a vertical section taken along the line II—II of Fig. 1.

In the drawing only such parts are shown as are necessary to an understanding of my invention. Other features usually found in jigs of this type are already well known and form no part of my invention.

My improved jig comprises a rectangular tank 10 containing partition walls 11 and 12 which, with the outer walls, define a hutch 13 and a water well 14. A perforated screen 16 extends over the upper part of the hutch, which screen is preferably inclined, as shown, to assist in the travel of coal thereover as it is being washed. Coal to be washed is fed on to the screen through a suitable feed chute 17 at one end thereof and travels, while it is being washed, toward the other end of the screen, the washed coal passing out over a weir 18, while the slate and rock, and other refuse, is discharged through a rotary slate

gate 19. The slate gate 19 is driven by any suitable means, not shown, which forms no part of my present invention.

Disposed within the hutch 13 beneath the screen 16 is a reciprocable plunger 21 having a plurality of valves 22 thereon which open on the down stroke of the plunger and close on the up stroke thereof to effect upward pulsations of water through the screen 16. The plunger 21 is reciprocated through rods 23 which extend downwardly through wells 24 in the screen 16, and which are connected at their upper ends to a counter shaft 26. The counter shaft 26 is connected through links 27 to eccentrics 28 which are mounted on a power shaft 29 driven from any suitable source through a gear 31.

Extending across the bottom of the hutch 13 is an inclined wall 32 having a plurality of valves 33 therein which open on the up stroke of the plunger 21 and close on the down stroke thereof. Water for the operation of the jig is supplied through the well 14 which communicates with the hutch wall 32. The partition wall 12 separates the hutch from the slate boot 34 into which the refuse is discharged and is removed therefrom by means of an elevator 36. At the lower end of the partition wall 12 is an opening 35 through which fines passing down through the screen and plunger are swept by the reciprocating action of the plunger into the slate boot 34. This opening is so restricted in size, however, that it does not materially affect the operation of the jig.

Extending part way across the tank 10 at the upper end of the screen 16 is an air compression chamber 37 which, as will be seen in Fig. 2, is closed at its upper end and opens into the hutch at its lower end. The air compression chamber extends upwardly a sufficient distance to provide a considerable volume for the compression and expansion of air therein as the plunger 21 reciprocates. In order to more clearly illustrate the invention, the chamber 37 is somewhat exaggerated in size in the drawing, but I have found that with a plunger approximately five feet by three feet six inches in total area, a chamber extending approximately two feet across the short dimension of the screen and approximately six inches inside width, provides sufficient space to cushion the movements of the plunger.

The operation of my improved jig will be apparent from the foregoing description. Upon the up stroke of the plunger 21, water is forced upwardly through the screen 16 effecting stratification of the coal and slate, while water is admitted to the hutch 13 beneath the plunger 21 by the opening of the valves 33. As the plunger 21 reaches the end of its up stroke and starts on its down stroke, the inertia of the moving body of water through the valves 33 is absorbed in the air compression chamber 37 so that the valves 33, instead of pounding as they close, are gently closed. The plunger 21 as it moves downwardly, with the valves 22 open, has its excess compressive force absorbed by the air cushion in the upper part of the chamber 37, the air being compressed by the upflow of water therein. Then, as the plunger 21 starts again on its up stroke, the air under compression in the chamber 37 assists the plunger and smooths out its operation.

By the simple provision of the air compression

chamber 37, I have greatly reduced the weight of the power shaft 29 and its bearings, and have reduced the power required to operate a jig of this type to less than one-half of the former requirement. For example, where it has formerly required a forty horse power motor to operate the jig, I have secured an improved operation on a similar jig with a fifteen horse power motor. In addition, the breathing action of the walls of the tank has been entirely eliminated and the valves have a more prolonged life.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In a jig, the combination of a screen, a reciprocable plunger for effecting upward pulsations of water through the screen and having valved controlled openings therein, means defining a hutch in which the plunger reciprocates including a wall having valved controlled openings for admitting water to the hutch, and an air compression chamber communicating with the hutch between the wall and the plunger, said chamber being closed at the top to provide for the compression and expansion of air therein as the plunger reciprocates.

2. In a jig, the combination of a hutch, a screen over the hutch, a plunger reciprocable in the hutch beneath the screen, valves in the plunger which open on the down stroke and close on the up stroke thereof, a confining wall for the hutch having valves therein which close on the down stroke and open on the up stroke of the plunger to admit water to the hutch, and means defining a chamber extending upwardly above the screen level, said chamber being closed at its upper end, and communicating with the hutch below the screen and the plunger.

3. In a jig, the combination of a hutch, a screen over the hutch, a reciprocable plunger fitting within the hutch beneath the screen, valves in the plunger which open on the down stroke and close on the up stroke thereof, a wall across the hutch beneath the plunger, valves in the wall which open on the up stroke and close on the down stroke of the plunger, and an air compression chamber extending across the hutch on one side and communicating with the hutch beneath the plunger.

4. In a jig, the combination of a hutch, a screen over the hutch, a reciprocable plunger fitting within the hutch beneath the screen, valves in the plunger which open on the down stroke and close on the up stroke thereof, a wall across the hutch beneath the plunger, valves in the wall which open on the up stroke and close on the down stroke of the plunger, and a chamber extending across one side of the hutch and opening thereinto beneath the plunger, said chamber extending upwardly alongside the hutch and being closed at its upper end to afford a space for the compression and expansion of air therein as the plunger reciprocates.

JAMES A. MONTGOMERY.
